UNITED STATES PATENT OFFICE

SANFORD JAY LOCKE AND FLOYD RAY WEBSTER, OF SYRACUSE, NEW YORK, ASSIGNEES
TO UNITED STATES HOFFMAN MACHINERY CORPORATION, OF NEW YORK, N. Y.,
A CORPORATION OF DELAWARE

PRESS

Application filed November 5, 1928. Serial No. 317,422.

This invention relates to garment presses and particularly the toggle mechanism used to actuate such presses.

Prior to the present invention it has been proposed to use a main toggle which reacted between the frame and the head-carrying lever in conjunction with a secondary toggle which commonly reacted between the frame and the primary toggle and which operated to straighten and break the primary toggle.

In a structure of this character one element of the primary toggle was commonly rendered adjustable as to its effective length.

The present invention departs from the practice of the prior art in that the primary toggle is not adjustable and is so dimensioned that it is never straightened in the pressing operation. The secondary toggle is arranged, however, to straighten at the moment of maximum pressure and is made manually adjustable as to its effective length so that the degree of maximum pressure is variable by an adjustment of the secondary toggle. This follows from the fact that adjustment of the secondary toggle varies the degree of straightening of the primary toggle.

There are definite advantages in this arrangement. In the first place no latch for the treadle which operates the secondary toggle is necessary. In the second place a considerable range of adjustment of maximum pressure can be secured. This follows from the fact that the primary toggle nearly but not quite straightens and consequently a wide range of pressure variation can be secured by a relatively limited adjustment of the effective length of the secondary toggle.

The term effective length of the secondary toggle is used in a generic sense, for while the drawings illustrate an embodiment in which the length of one of the toggle links is varied, it is a fact well known to those skilled in the art that the same result can be secured by varying the length of either link or by shifting the point of attachment of either link to the frame or lever against which it reacts. Except as specified in the claims, limitation to the particular arrange-

ment chosen for illustration is not contemplated.

The preferred embodiment of the invention as applied to a lever press is illustrated in the accompanying drawings in which,

Figure 1 is a side elevation of a garment press having the invention applied, certain parts of the frame being sectioned to show the construction. The parts are shown in the position assumed when the press is closed and under pressure.

Figure 2 is an enlarged elevation partly in section showing the secondary toggle mechanism and the adjusting means therefor.

Figure 3 is a plan view of the parts shown in Figure 2 with portions of the machine frame in section.

Figure 4 is a section on the line IV—IV of Figure 2.

The base frame of the press is indicated at 6 and has at its rear an upward extension 7 upon which the head lever is pivoted as hereinafter described.

The base 6 supports a work table 8 and by means of the usual C-shaped bracket 9 sustains a buck 11 of conventional form. Co-acting with the buck 11 is a pressing head 12 which is supported on the head lever 13. This head lever is counterweighted at 14 and is pivoted at 15 on the upward extension 7 of the base 6.

A handle by means of which the operator may draw the head 12 down against the buck 11 is illustrated at 16.

Steam valves and all accessory apparatus for the head and buck are omitted.

A spring 17 reacting between the lever 13 and the base plate of the frame 6, serves to urge the press in an opening direction.

All the parts so far described are of ordinary construction. No novelty is claimed for them and they are subject to wide variation. In fact the invention is not limited in its utility even to lever presses.

Pivoted at 18 on the lever 13 and at 19 on the base frame 6 is the primary toggle made up of a long lower link 21 and a shorter upper link 22 hinged to each other at 23. This primary toggle conforms to prior prac-

tice except that no means need be provided to adjust its effective length and that its effective length is such that the maximum closing pressure between the head 12 and 5 buck 11 is exerted before the primary toggle reaches its straightened position.

Pinned to link 21 of the primary toggle at 24 and pivoted on the frame 6 at 25 is a secondary toggle made up of two links 10 pivoted together at 26. The rear link 27 in the example illustrated is non-adjustable. The front link is adjustable and comprises a portion 28 pivoted at 25, as above described, and a companion portion 29 pivoted to the 15 link 27 at 26. The portion 28 carries an offset sleeve 31. The sleeve 31 and the portion 29 are reversely threaded to form with a reversely threaded rod 32 a sort of turn-buckle.

20. The rod 32 has an extension 33 which projects through a slot 34 formed in a portion of the base frame 6 and terminates in a hand wheel 35 by means of which the rod 32 may be turned to vary the length of the link 28, 25 29,—that is the distance between the axis of the pivots 25 and 26. When the adjustment has once been made the parts are locked by a check-nut 36. Various equivalent ways 30 of adjusting the length of the link 28, 29 might be adopted but the one shown is preferred because it is strong and simple and because in presses of ordinary design the hand wheel 35 is at the front of the press and readily accessible. It must be understood, however, that the purpose of the adjustment is primarily to adjust the effective length of the secondary toggle. This 35 is another way of saying that the adjustment determines the position of the axis of 40 the pivot 23 when the secondary toggle is straightened and it is within the broad scope of the invention to effect this adjustment in other ways than the one specifically illustrated.

45. The primary toggle is constantly urged in a press opening direction by a coil tension spring 37 which reacts between a stud 40 on the link 21 and a portion of the frame 6. The secondary toggle may be straightened by 50 depressing a pedal 38 which is mounted at the forward end of a lever 39. The lever 39 is pivoted at 41 on the base frame 6 and is connected to the toggle link 28 by links 42. These are pivoted to the lever 39 at 43 and 55 to the link 28 at 44. The toggle may be opened by lifting the foot piece 38 either directly or by means of a kick-off treadle which is of well known form and not being a feature of the present invention is not illustrated.

60. The operation of the press will be readily understood but it should be observed that the construction is such that the hand wheel 35 is immediately above the pedal 38 so that the 65 adjustment may be conveniently effected and

its effect noted from the operator's station at the front of the press. The arrangement is simple and the use of an adjustable secondary toggle which does straighten in combination with a primary toggle which does not straighten in the operation of the device gives a wide range of pressure adjustment, avoids the necessity for any latch to hold the pedal 38 down and produces a press which has a smooth gradual opening movement.

70. What is claimed is:

1. In a press, the combination of a support; a buck mounted thereon; a head adapted to cooperate with the buck; a member movably mounted on the support and arranged to support and guide the head in movements toward and from the buck; a toggle connected to react between said member and support and so dimensioned that the toggle approaches but does not reach a straightened 80 position when the head exerts its maximum pressure against the buck; a second toggle arranged to actuate the first toggle; means for adjusting the second toggle, said means extending forwardly of the toggle in a position where it may be readily adjusted by the operator; and means for straightening the second toggle.

2. In a garment press the combination of 85 a main frame; a buck mounted thereon; a lever pivoted intermediate its ends upon the upper portion of the frame; a head carried at that end of the lever which extends above the buck; a toggle interposed between the rear end of the head-carrying lever and a fixed portion of the main frame; a second toggle interposed between said toggle and a fixed portion of the main frame, said second toggle consisting of a pair of links, one of said links being pivotally connected to an element of the first named toggle, and the second link consisting of two members, one member being pivotally connected to the adjacent end of the other link and having its other end internally threaded, a second member pivoted to a fixed portion of the main frame, said second member being formed with an offset, internally threaded portion, the threads whereof are the reverse of those in the other member; and a threaded rod engaging said 100 threaded portions and extending forwardly of the toggle to the front of the machine where it may be readily adjusted by the operator to vary the effective length of said second member and consequently the effective 105 length of the second toggle; and means for actuating said second toggle.

110. In testimony whereof we have signed our names to this specification.
